Inventor.

UNITED STATES PATENT OFFICE.

WILLIAM C. FINCK, OF ELIZABETH, NEW JERSEY.

DESIGN FOR A LACE-PIN.

SPECIFICATION forming part of Design No. 20,837, dated June 16, 1891.

Application filed March 2, 1891. Serial No. 383,485. Term of patent 14 years.

To all whom it may concern:

Be it known that I, WILLIAM C. FINCK, a citizen of the United States, residing at Elizabeth, Union county, New Jersey, have invented a certain new and Improved Design for Ornamental Pins, fully described and represented in the following specification and the accompanying drawings, forming a part of the same.

- 10 This design relates to that class of pins which are applied to ladies' clothing for ornamental purposes and adapted for use either separately or in connection with a society-badge; and the design consists in a shape 15 and configuration for such pin comprising a shepherd's crook having a straight smooth shank tapered to a point at one end and having its other end of angular cross-section and twisted and bent into a reflex curve to form 20 the head of the same. The pin is shown in the annexed drawing having a badge in the shape of a Maltese cross attached thereto.

a is the shank of the pin, which is tapered to a point at one end and has the ornamented head *b* at the opposite end. The end of the *a* 25 wire comprising the pin is made of angular cross-section and twisted, in addition to its being bent into a reflex curve, to form the head to give the latter its spiral appearance. A badge *c* is shown depending from an eye *e* 30 upon the shank adjacent to the head *b*; but such features of the article shown herein form no part of my present design.

What I claim herein is—

The design for an ornamental pin herein 35 shown and described.

In testimony whereof I have hereunto set my hand in the presence of two subscribing witnesses.

WILLIAM C. FINCK.

Witnesses:

HENRY J. MILLER,
DANIEL TYLER.
